JAMES HARVEY HUNTER, OF OMAHA, NEBRASKA.

METHOD OF HARNESSING THE UNDERFLOW ADJACENT TO STREAMS IN SANDY STRATA.

1,125,848.

Specification of Letters Patent.

Patented Jan. 19, 1915.

Application filed March 3, 1914. Serial No. 822,180.

To all whom it may concern:

Be it known that I, JAMES HARVEY HUNTER, a citizen of the United States, and a resident of Omaha, in the county of Douglas and State of Nebraska, have devised an Improved Method of Harnessing the Underflow Adjacent to Streams in Sandy Strata, of which the following is a specification.

Our western rivers such as the Platte, 10 Niobrara, Smoky Hill, the Arkansas, and many others have much similarity in general features, and have a fall of from seven to fifteen feet to the mile. The valleys or land lying along these rivers are of great width, 15 in some places fifteen miles wide, and underneath the top layer of black soil there is a stratum of pure merchantable sand, sometimes extending to a depth of ninety feet or even more, and underneath this stratum is 20 a rock bottom.

The sand-bed is full of water which slowly percolates down the stream, adjoining a river. The variation in the depth of the water in the river and the adjacent sand 25 stratum is not more than eighteen inches throughout the year, high water being in the early spring time and low water in August and September.

I have devised a new and successful 30 method for obtaining clear water from the sand stratum which is conducted off downstream, or to any desired point where it is available for irrigation, or power purposes, or for supplying towns or cities.

35 In carrying out my invention, I first dig a trench large enough for the pipe to be used, the latter being generally from four to ten feet in diameter. The trench is dug to a depth that will allow the top of the pipe 40 to be covered by the water at least one foot below low water level, and the trench has a fall of one foot or more to the mile; and, as the top surface of the land has a still greater inclination, it is apparent that the 45 pipe will come out above the soil at a greater or less distance from its mouth or upper end. From there on the pipe may be laid above ground and extended to any desired point, or where the water is to be delivered either 50 into ditches, or for power purposes, or city supply.

If the water is used for irrigation purposes only, then it of course suffices to discharge on the top of the ground into ditches 55 or reservoirs; and for city purposes the pipe

will connect with suitable smaller distributing pipes.

When the pipe is laid in the trench, as above stated, its upper end must be closed by means of a cap or other device, in order 60 to keep out the water until the operation is completed; that is to say, until a large excavation shall have been made in the sand. Thus the first step consists in digging the ditch or trench to the required depth and 65 rolling into it a long length of pipe which has been weighted with a cement band in order to hold it under water. The pipe is then covered, except at the lower end where the work of extending it is continued. 70 Powerful pumps are employed to keep the water out of the ditch until it gains such a level as will not be necessary. An excavation is then made, the lower or top soil being first removed, thus exposing a clean sand 75 stratum.

The sand may be excavated by any suitable machinery, and, in practice, loaded on cars, since it is a commercial article of 80 considerable value.

The next step consists in uncapping or unclosing the end of the pipe which projects into the excavation. The underflow fills the excavation as fast as it is made, and the size of the excavation will depend upon circumstances, particularly upon the diameter of the pipe line, the downward inclination of the same, etc. Thus, when the operation is complete, a perpetual flow of pure water 85 through the pipe is assured. There is 90 scarcely any limit to the number of pipes that can be laid and concentrated into one large pipe or reservoir after reaching the top of the ground.

My method is illustrated in the accompanying drawing, in which—

Figure 1 shows a pipe line *a* laid in a water bearing stratum of sand *b*, it being understood that a trench has been dug to the required depth and the pipe line laid 100 therein and covered with sand. Fig. 2 is an illustration of the necessary steps in the method, which consist in digging the required excavation to the required depth *c* around and adjacent to the mouth of the pipe, and then removing the cap which previously closed it as shown in Fig. 1. In Fig. 3, the pipe line is shown constructed of longitudinal staves bound by bands of iron *e* and weighted by cement bands *f*, which 105 110

serve to hold it firmly in place under water in the sand.

It is to be understood, however, that the pipe may be constructed of other material, 5 for instance, of sheet-steel sections riveted together.

The pipe must be sunk at least one foot below the lowest water mark in order to insure a continual flow. It will be further understood that the pipe-laying must be complete before the pond or reservoir can be dug, since the water would be entirely uncontrollable if the latter were made first; and this is the chief point or merit of my 10 method or system.

In selecting a locality for the pond or reservoir, I prefer a tract of 80 acres or thereabout, and this is of course adjacent to a river, preferably where the banks are low 20 and the underflow is near the surface. It is apparent that if the mouth of the pipe were not closed until the operation is otherwise complete, the water in the trench would naturally prevent men from working, and 25 the water would be required to be pumped

out of the trench. By closing the mouth of the pipe the flow through the latter is prevented, but pumping of the water from the trench is necessary, and, when half a mile of pipe is laid in the trench, the pipe can 30 usually be laid near the top of the ground, where it is then an easy matter to proceed with the further construction.

What I claim is:—

The method hereinbefore described consisting in digging a trench from a point upstream to a point down-stream in a water-containing sand stratum, to a depth below the low water level; then laying in said trench a pipe whose upper end is closed; then excavating the sand adjacent to and around the closed upper end of the pipe, to form a reservoir of a required capacity; and finally unclosing the exposed end of the pipe, as described. 40

JAMES HARVEY HUNTER.
